UNITED STATES PATENT OFFICE.

IRVING C. JENNINGS, OF SOUTH NORWALK, CONNECTICUT.

ADJUSTING AND SECURING MEANS FOR AIR-PUMP ROTORS.

Application filed May 3, 1926. Serial No. 106,297.

This invention, while capable of general application, is particularly adapted for securing the rotor of a hydro-turbine air pump to its supporting shaft. Such air pumps are

5 frequently used for priming centrifugal suction pumps and in such a construction the rotor of the air pump is often mounted directly upon a rigid extension of the centrifugal impeller shaft, while the casing of the air pump 10 is rigidly secured to the centrifugal pump casing.

The air pump rotor must be accurately adjusted axially to provide the necessary clearance at both sides of the rotor and must also 15 be firmly secured to its driving shaft.

It is the object of my invention to provide an improved construction by which an air pump rotor or other similar rotatable member may be accurately adjusted axially on its 20 supporting shaft and may be securely retained in adjusted position.

My invention further relates to arrangements and combinations of parts which will be hereinafter described and more particularly pointed out in the appended claims.

Several forms of my invention are shown in the drawings in which

Fig. 1 is a sectional elevation of an air pump embodying my improvements;

30 Fig. 2 is a partial sectional elevation, showing a slight modification;

Fig. 3 shows a special form of washer which may be used with my invention; and

Fig. 4 is a sectional elevation of a further modification.

Referring to Fig. 1, I have shown a portion of an air pump of the hydro-turbine type, comprising a casing member 10 forming one side of an air pump chamber 11, and a cover member 12 forming the periphery and the outer side wall of the chamber 11. The casing members 10 and 12 are rigidly supported upon a frame 13, commonly forming a part of a centrifugal pump casing.

45 The pump impeller shaft 15 extends through a stuffing box 16 and through the air pump casing member 10, and is provided with a flange or shoulder 17, loosely rotatable in an opening 18 in the inner side wall of the 50 air pump chamber 11. The flange or shoulder 17 is so positioned that its outer face will be back of the plane of the inner face of the air pump or rotor chamber.

The rotor 20 is slideable on the outer end 55 portion 21 of the shaft 15 and may be secured thereon by a binding screw 22, having

an enlarged head projecting over the hub 23 of the rotor 20. The end portion 21 of the shaft does not project quite to the outer end of the hub 23.

60 The method of adjusting the rotor upon the shaft 15 is as follows:

The casing 10 is first secured to the frame 13, as by clamp screws 24, and careful measurement is then made with a depth gauge, 65 or in any other convenient manner, to accurately determine the distance from the outer face of the flange 17 to the inner face of the rotor chamber.

An allowance is then made to give the desired clearance of the rotor in the rotor chamber, and a spacing member 25 of the determined thickness is then slipped onto the end portion 21 of the shaft and against the flange 17. This spacing member may be 75 conveniently formed by assembling the required number of very thin discs or washers to build up the desired thickness.

The rotor 20 is then placed on the portion 80 21 of the shaft and is clamped against the spacing member 25 by the binding screw 22. The rotor is thus held firmly upon the end of the shaft and is accurately spaced between the walls of the chamber 11, this accurate spacing being attained without requiring accurate machine work to accomplish the result.

85 Instead of forming the spacing member 25 from a plurality of thin discs or washers, I may use a single washer such as is shown at 27 in Fig. 3, this washer being made up of 90 spirally arranged layers of very thin material, with the separate layers soldered or otherwise secured together. One or more layers may be peeled off to reduce the washer to the desired thickness.

95 Obviously, a unitary washer 28 (Fig. 2) may be reduced to the desired thickness by grinding or in any other convenient manner, or a washer 28 of the desired thickness may be selected from a stock of washers of different thicknesses.

100 In Fig. 2, I have indicated the use of a washer 28 of unitary structure in a slightly modified construction in which the pump shaft 30 is provided with a threaded extension 31 on which a binding nut 32 is mounted to engage the hub 23 of the rotor 20, as in the form previously described.

105 In Fig. 4, I have a construction in which a recess 40 is formed in the hub 41 of the rotor 42. The shoulder 43 of the shaft 44 may be substantially in the plane of the inside of the

casing 45 and a spacing washer 46 is provided, of such thickness as will provide the desired clearance for the rotor in the casing 45. The rotor is held in position by a binding screw 47 as previously described. This construction embodies many of the advantages of the forms previously described.

It will be understood that any one of the three forms of washers shown and described 10 may be used with the construction shown in either Fig. 1, Fig. 2 or Fig. 4.

Having thus described my invention and the advantages thereof, I do not wish to be limited to the details herein disclosed otherwise than as set forth in the claims, but what 15 I do claim is:

1. In a pump, in combination, a casing having outer and inner walls and an axial opening through said inner wall, a shaft having 20 a shoulder rotatable in said opening but positioned back of the plane of the inner face of said casing, an impeller having a hub slidable axially on said shaft, and a rotatable body portion extending between the walls of 25 said casing, a spacing member of selected thickness interposed between said shaft shoulder and the adjacent end of said hub, and means to press said hub against said spacing member and shoulder, thereby securing 30 said rotatable portion of the impeller in an accurate spaced position with respect to said walls.

2. In a pump, in combination, a casing having outer and inner walls, and an axial 35 opening through said inner wall, a shaft hav-

ing a shoulder rotatable in said opening but positioned back of the plane of the inner face of said casing, an impeller having a hub slidable axially on said shaft, and a rotatable body portion extending between the walls of 40 said casing, a spacing member of selected thickness interposed between said shaft shoulder and the adjacent end of said hub, the outer end of said shaft terminating within 45 said hub and back of the outer end surface of said hub when the impeller is in axially adjusted position with respect to the walls of the casing, and threaded means engaging the end of said hub to press said impeller axially along said shaft.

3. In a pump, in combination, a casing having outer and inner walls with an axial opening through said inner walls, a shaft having a shoulder rotatable in said opening but positioned back of the plane of the inner face of said casing, an impeller having a hub slidable on said shaft, and a rotatable body portion extending between the walls of the casing, a variable plurality of very thin washers interposed between said shaft shoulder and the adjacent end of said hub, and means to press said hub firmly against said washers and shoulder thereby accurately positioning the rotatable body portion axially in said casing and securing said hub to said shaft.

In testimony whereof I have hereunto affixed my signature.

IRVING C. JENNINGS.
